REFRIGERATOR APPARATUS

Oscar M. Anderson, New Britain, Conn., assignor to Landers Frary & Clark, New Britain, Conn., a corporation of Connecticut

Application December 15, 1936, Serial No. 115,969

4 Claims. (Cl. 312—150)

This invention relates to refrigerators and, more particularly, to a hydrator within a refrigerator cabinet arranged to maintain vegetables and other produce in a fresh, moist condition, and has for its principal object the provision of an easily removable hydrator pan or container which is so supported that cold air is not directed onto the produce therein but is free to circulate about the container.

10 It is another object of this invention to provide a shelf within a refrigerator having a plate removably secured thereto forming a part of the shelf and which is adapted to removably support a vegetable container therebeneath.

15 It is a further object of this invention to provide a refrigerator shelf containing a combined supporting plate and cover for a pan or container and which may be readily removed from the shelf for cleaning without removing the shelf 20 from the refrigerator.

Other objects will be in part obvious and in part pointed out more in detail hereinafter.

The invention accordingly consists in the features of construction, combination of elements 25 and arrangement of parts which will be exemplified in the construction hereafter set forth and the scope of the application of which will be indicated in the appended claims.

In the drawings illustrating one embodiment 30 of the present invention:

Figure 1 shows a fragmentary portion of a refrigerator cabinet having my invention mounted therein;

Fig. 2 is a side elevation of a refrigerator shelf 35 supporting my hydrator;

Fig. 3 is a plan view of the hydrator; and

Fig. 4 is an enlarged fragmentary view showing the means whereby the supporting plate of my hydrator may be assembled with a shelf.

40 In accordance with my invention, I have provided a hydrator for a refrigerator cabinet 10 and which, in general, comprises a container or pan P slidably mounted on the under side of a supporting plate 11 which is removably mounted within a shelf 12 and serves the dual purpose of a part of the shelf and a support and cover for the pan P.

45 Shelf 12, as herein illustrated, has a metal frame 14 formed from a bar bent to rectangular 50 shape and having substantially parallel spaced front and rear members 15 and 16 and substantially parallel spaced end members 17 and 18. The front and rear members are interconnected by spaced cross bars 19 to provide a supporting 55 shelf which will not materially interfere with the

circulation of cold air in the food compartment. The end members 17 and 18 are suitably supported within cabinet 10 upon projecting lugs or studs 20 mounted in the opposite side walls of the cabinet. Each of these studs preferably has 5 enlarged heads 20' at their opposite ends interconnected by a reduced neck portion 20'', and these reduced neck portions receive frame members 17 and 18 and support the shelf so that it will not normally move into contact with the 10 side walls of the cabinet. A pair of spaced parallel cross bars 21 are respectively secured at their opposite ends in any suitable manner, as by soldering or welding, to intermediate portions of frame members 15 and 16 so that plate 11 15 may be received within the rectangular aperture formed by members 15, 16, and bars 21. It will be understood, of course, that bars 21 may be located wherever desired, or only one bar 21 may be used and plate 11 may be supported between 20 this bar and the end of the frame without departing from the scope of the present invention.

25 Plate 11 which serves as a removable part of shelf 12 has a flat top face 22 located substantially in the plane of the top of the shelf. The sides of the plate are bent downwardly and inwardly providing side forces 23 terminating in opposed inturned flanges 24 adapted to slidably receive the top peripheral flange 25 of pan P so that the tray may be slid into and out of position beneath the shelf. A handle H may be provided on the pan to conveniently slide the pan into and out of position. The forward and rearward ends of top face 22 are preferably downturned, as at 27, to add rigidity to the plate. The 30 plate is removably supported between bars 21 by lugs or studs 30 secured in spaced relation to the opposite sides of the plate as by screws 31.

35 In the present instance, a pair of the studs 30 are mounted in opposed relation near each end of the plate. These studs may be similar in form to the shelf supporting studs 20 and terminate at their ends in enlarged heads 32 interconnected by a neck portion 33. The forward set of studs have their neck portions respectively 40 received within depending loops 34 formed in the forward ends of bars 21. The rearward pair of studs are supported in corresponding relation beneath bars 21 by correspondingly located offset brackets 35. Each of these brackets is formed 45 from a bar bent to shape having two spaced arms 36 and 37 interconnected by an offset portion 38. Arms 36 are respectively secured beneath bars 21, as by welding or soldering, thus locating arms 50 37 in spaced relation beneath the respective bars 55

so that they slidably engage and support neck portions 33.

- It will thus be appreciated that the rearward set of studs 30 located near member 16 are slidably mounted on arms 37, and the forward set of studs 30 are normally received within the depending U-shaped seating portions 34, thus preventing slidable movement of plate 11 and locating it substantially centrally of and in spaced relation between bars 15, 16, and 21 so that the top face 22 forms a continuation of the shelf and pan P is free to be slidably located under the shelf or withdrawn therefrom without causing movement of the plate. When it is desired to remove the plate for cleaning, it is simply necessary to remove pan P, after which the forward portion of the plate may be tilted upwardly, lifting studs 30 out of their seats 34, and the plate may thereafter be slid forward, disengaging the rearward studs from arms 37. A twisting movement of the plate will now put it in a position where it may be lifted from the shelf and easily removed for cleaning without disturbing the shelf or articles supported thereon.
- As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a refrigerator, a metal shelf composed of a pair of spaced longitudinal members interconnected by spaced parallel cross members, a plate located between a pair of said cross members and having depending side faces, inturned supporting flanges on said side faces slidably en-

gaging and supporting a pan therebeneath, spaced studs laterally extending from each of said side faces, and means on said pair of cross members removably receiving said studs.

2. In a refrigerator shelf having spaced cross members, a hydrator cover received between a pair of said cross members, a pair of studs laterally protruding from each side of the cover, depending U-shaped portions on the said pair of cross members respectively and detachably receiving two of said studs, brackets secured to the under sides of the cross members slidably receiving said other studs, and means on said cover slidably supporting a pan therebeneath.

3. In a metal refrigerator shelf having a pair of spaced longitudinal bars interconnected by cross members, a hydrator cover between two of said cross members and forming a part of said shelf, depending side walls on the cover, a pair of studs laterally and respectively projecting in opposed relation from said side walls adjacent the front of the cover, said two cross members being provided with seating portions adapted to receive said studs, a second pair of studs laterally and respectively projecting from the opposite sides of the cover adjacent its rearward end, a pair of brackets respectively mounted on said two cross members beneath their rearward ends and slidably receiving said pair of rearwardly disposed studs, and inturned flanges at the bottoms of said side walls adapted to slidably support a hydrator pan therebeneath.

4. In a refrigerator, a shelf having cross members connected with longitudinal frame members, a hydrator cover positioned between a pair of cross members and having depending sides slidably supporting a hydrator pan therebeneath, supporting means laterally protruding from said depending sides of the plate, and depending means carried by said cross members and adapted to removably engage said supporting means in position to align said cover with the plane of the shelf.

OSCAR M. ANDERSON. 45
